UNITED STATES PATENT OFFICE.

EDWARD A. GEHRKE, OF LINCOLN, NEBRASKA.

BALL-COCK FOR FLUSH-TANKS.

1,096,237.

Specification of Letters Patent.

Patented May 12, 1914.

Application filed February 21, 1913. Serial No. 749,950.

To all whom it may concern:

Be it known that I, EDWARD A. GEHRKE, a citizen of the United States, residing at Lincoln, in the county of Lancaster and State of Nebraska, have invented a new and useful Ball-Cock for Flush-Tanks, of which the following is a specification.

The invention relates to improvements in ball cocks for flush tanks.

10 The object of the present invention is to improve the construction of ball cocks for flush tanks, and to provide a simple, inexpensive and efficient cock or valve mechanism, having a straining device and equipped with a catch basin accessible exteriorly of the flush tank, and adapted to be easily cleaned without removing the valve from the flush tank.

With these and other objects in view, the 20 invention consists in the construction and novel combination of parts hereinafter fully described, illustrated in the accompanying drawing, and pointed out in the claims here-to appended; it being understood that various changes in the form, proportion, size 25 and minor details of construction, within the scope of the claims, may be resorted to without departing from the spirit or sacrificing any of the advantages of the invention.

30 In the drawing:—Figure 1 is a vertical sectional view of a ball cock embodying the invention and constructed for use in deep flush tanks. Fig. 2 is a similar view of a relatively short ball cock. Fig. 3 is a detail 35 perspective view of the lower interiorly arranged tube.

Like numerals of reference designate corresponding parts in all the figures of the drawing.

40 In the accompanying drawing in which is illustrated the preferred embodiment of the invention, 1 designates a main vertical tube, provided with a threaded lower portion 2, extending through an opening 3 in the bottom 4 of a flush tank and equipped at the upper face of the bottom 4 with a collar 5, which coacts with a lower nut 6 in securing the tube 1 to the bottom of the flush tank. The bottom of the flush tank is clamped between the collar 5 and the nut 6, a gasket 7 45 of rubber, or other suitable material being preferably interposed between the nut 6 and the bottom of the flush tank, but the connection between the tube and the bottom of the flush tank may be rendered water tight in 50 any other suitable manner.

The lower threaded portion 2 of the vertical tube 1 depends below the bottom 4 of the flush tank, and it is provided at its lower end with an interior annular recess 8, formed by an inwardly projecting annular flange 9 and receiving an outwardly extending annular flange 10 of an interiorly arranged tube 11 of considerably smaller diameter than the tube 1 and extending upwardly into the same in spaced relation with the said tube 1 to provide an intervening annular space to form a catch basin 12 for holding sand, gravel and other accumulation entering the ball cock. When the tube 1 is of considerable length, as illustrated in Fig. 1 of the drawing, the interiorly arranged tube 11 is preferably of a length to extend above the bottom 4 of the flush tank, but it may, of course, be of any desired length, and the annular flange 10 thereof is located near the end of the tube 11, which receives an elastic gasket 13 of rubber, or other suitable material fitted against the lower face of the annular flange 10 and being of greater diameter than the same to fit against the lower end of the tube 1 and extended to the outer face of the same to provide a water tight joint at this point. The tube 11 is detachably retained within the lower portion of the tube 1, and the gasket 13 is held firmly against the lower end of the same by means of a union 14, threaded to engage the exterior screw threads of the tube 1 and provided at the bottom with an inwardly extending flange 15, which is adapted to engage beneath an outwardly extending flange 16 of a short tube or nipple 17. The short tube or nipple 17, which has an exteriorly threaded lower end, is designed to be connected to a suitable supply pipe, but the pipe 17 may be of any desired length and may constitute a considerable portion of the supply pipe.

55 The interiorly arranged tube 11 is provided above the annular flange 10 with a drain opening 18, adapted to permit water to drain from the catch basin when the short tube or nipple 17 is uncoupled from the main tube 1. When it is desired to clean the catch basin, the water is turned off and the union 14 is unscrewed from the lower end of the vertical tube 1 and the interiorly arranged tube is removed therefrom and with it the accumulation contained within the catch basin, the upper face 19 of the interior annular flange 9 being beveled to pre-

vent any of such accumulation from lodging on the flange. After the catch basin has been cleaned, the parts may be quickly re-coupled, the elastic gasket 13, which is carried by the lower portion of the tube 11, enabling a water tight joint to be made between the nipple, the interiorly arranged tube 11 and the vertical tube 1.

The upper end of the vertical tube 1 is 10 interiorly threaded to receive a screw plug 20, constituting a top for the vertical tube 1 and provided with a threaded opening 21 of considerably less diameter than the interior of the tube 1 and receiving an upper adjustable interiorly arranged tube 22, provided with exterior threads 23 to engage the threaded opening in the plug 20 and having a strainer 24 of wire gauze, or other suitable material at its lower end. The upper 20 end of the tube 22 extends above the plug 20 and constitutes a seat for a vertically movable valve, consisting of a plunger composed of upper and lower sections 25 and 26. The lower portion of the upper tube depends below 25 the plug and is arranged in spaced relation with the tube 1. The adjustment of the upper tube also enables a proper closing action of the valve to be obtained and will take up any wear of the parts. The lower 30 section is provided in its lower end with a circular recess 27 for the reception of a disk 28 of rubber, leather, or other suitable material to engage with the upper end of the tube 22, which forms the valve seat. The lower 35 section is provided with a tapered upper portion 29, and it has a threaded terminal stem or portion 30, which screws into a threaded socket 31 in the lower end of the upper section 25, a suitable packing 33 being arranged on the tapered portion 29 of 40 the lower section and adapted to be expanded by the same into close contact with the interior of a valve casing 34 to prevent the valve from leaking. The upper section 45 of the valve is provided with a transverse slot 35 through which extends a lever 36, connected at one end by a pivot 37 to a pair of projecting ears 38 of the valve casing. The other end of the lever 36 is connected 50 by a link 39 with a short angularly disposed arm 40 of a float controlled lever 41, fulcrumed by a suitable pivot 42 between upwardly, projecting ears 43 and having a ball float 44 secured to its outer end. The 55 lever 36 is provided at an intermediate point with a rounded portion 45 operating in the slot or aperture 35 of the upper section of the valve. The float 44 operates the lever 41 and the valve in the usual manner.

60 The valve casing is interiorly threaded at its lower portion at 46 to screw on a threaded upper portion of the plug 20, which is provided at points intermediate of its upper and lower ends with a flange 47, fitting against 65 the upper edges of the tube 1 and support-

ing a gasket 48 of rubber, or other suitable material. The gasket 48 is interposed between the valve casing and the flange of the plug and forms a water tight joint. The valve casing is provided at one side with a 70 discharge pipe 49, consisting of a short upwardly extending horizontal arm and a relatively long depending arm, which terminates a short distance above the bottom of the flush tank. The discharge pipe 49 delivers 75 the water to the flush tank close to the bottom thereof, and is adapted in a great measure to eliminate the noise, which would result from a considerable fall of water. The top horizontal arm of the pipe 49 preferably 80 supports the ears 43, and the said pipe 49 is also provided at the top portion with an interiorly threaded tubular extension or nipple 50 into which is screwed the inner threaded end 51 of a relatively small discharge tube 52. The valve casing is provided with an extended exteriorly threaded upper portion 53, and it is closed by a safety 85 interiorly threaded cap 54.

In Fig. 2 of the drawing is illustrated another form of invention, in which a relatively short vertical tube 55 is employed instead of the relatively long tube 1 heretofore described. The tube 55 is provided with an integral top 56 having a reduced threaded 90 opening to receive an upper adjustable strainer carrying tube 57, which coacts with a valve 58, constructed similar to that heretofore described. The valve casing 59 is also constructed substantially the same as the 100 valve casing before described with the exception that a short horizontal discharge tube 60 is employed.

What is claimed is:

1. The combination with a flush tank, of 105 a ball cock extending through the bottom of the flush tank and provided between its ends with means for securing it to the said bottom and extending below the same and having an interior annular recess at its lower 110 end, an interior vertical tube provided near its lower end with an exterior annular flange fitting in the recess, said interior tube extending into the main tube and arranged in spaced relation with the same to form a catch basin, and a union connected with the lower end of the main tube for coupling a supply pipe to the same and detachably retaining the interior tube within the vertical 115 tube.

2. The combination with a flush tank, of 120 a ball cock including a main vertical tube extending through the bottom of the flush tank and provided at its lower end with an interior annular flange beveled at its upper face and spaced from the lower edge of the vertical tube to form an interior annular recess, an interior vertical tube provided near its lower end with an exterior annular flange 125 arranged in the said recess and fitting 130

against the said interior flange, said interior tube being arranged in spaced relation with the main tube to form a catch basin, a gasket arranged on the lower end of the interior tube and fitting against the flange thereof and against the lower end of the main tube, and a union arranged on the lower end of the main tube and engaging the gasket and detachably retaining the vertical tube in position.

3. A ball cock of the class described including a main vertical tube interiorly threaded at the upper end, a screw plug engaging the threads of the vertical tube and constituting a top for the same and having a threaded opening of less diameter than the said tube, an upper interior vertical tube

exteriorly threaded and adjustably mounted in the said threaded opening and projecting above the top of the main tube and depending into the latter and provided at its lower end with a strainer, a valve casing connected to the upper end of the main tube, and a valve operating within the casing and co-acting with the upper end of the adjustable tube.

In testimony, that I claim the foregoing as my own, I have hereto affixed my signature in the presence of two witnesses.

EDWARD A. GEHRKE.
